[57] CLAIM

The ornamental design for a wrist supporting weight lifting dumbbell, as shown and described.

DESCRIPTION

FIG. 1 is a perspective view of the wrist supporting weight lifting dumbbell;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a back view thereof;

FIG. 8 is a top view thereof, the broken line showing of a user's hand is for illustrative purposes only and forms no part of the claimed design;

FIG. 9 is a bottom view thereof, the broken line showing of a user's hand is for illustrative purposes only and forms no part of the claimed design; and,

FIG. 10 is a cross-sectional view thereof, the broken line showing of a user's hand and forearm is for illustrative purposes only and forms no part of the claimed design.
